US00D539036S

(12) **United States Design Patent** (10) **Patent No.:** **US D539,036 S**
(45) **Date of Patent:** **** Mar. 27, 2007**

(54) **MULTI-POSITIONABLE CADDY AND ORGANIZER SYSTEM**

(76) Inventors: **Kenneth Lee Potts**, 462 Santa Cecelia, Solana Beach, CA (US) 82075-1505; **Debra Lee Potts**, 462 Santa Cecelia, Solana Beach, CA (US) 92075-1505

(**) Term: **14 Years**

(21) Appl. No.: **29/210,019**

(22) Filed: **Jul. 26, 2004**

(51) **LOC (8) Cl.** **03-01**

(52) **U.S. Cl.** **D3/311; D3/310; D12/425**

(58) **Field of Classification Search** D3/310-312, D3/309, 305, 315, 319, 313; D12/425, 426, D12/415, 423; D34/1; D9/432; 224/539, 224/425

See application file for complete search history.

(57) **CLAIM**

The ornamental design for a multi-positionable caddy and organizer system, as shown and described.

DESCRIPTION

FIG. 1 is a perspective view of one embodiment according to the invention;

FIG. 2 is a perspective view of an alternate position according to the invention;

FIG. 3 is a side view of the embodiment shown in FIGS. 1 and 2;

FIG. 4 is a bottom view of the embodiment shown in FIGS. 1 and 2;

FIG. 5 is a perspective view of an alternate position according to the invention;

FIG. 6 is a perspective view of an alternate position according to the invention;

FIG. 7 is a side view of the embodiment shown in FIGS. 5 and 6;

FIG. 8 is a perspective view of an alternate position according to the invention;

FIG. 9 is a perspective view of an alternate position according to the invention;

FIG. 10 is a side view of the embodiment shown in FIGS. 8 and 9;

FIG. 11 is a bottom view of the embodiment shown in FIGS. 8 and 9;

FIG. 12 is a perspective view of an alternate position according to the invention;

FIG. 13 is a side view of the embodiment shown in FIG. 12; and,

FIG. 14 is a bottom view of the embodiment shown in FIG. 12.
